SPOON OR SIMILAR ARTICLE

Colin B. Richmond II, Oneida, N.Y., assignor to Oneida Ltd., Oneida, N.Y.

Filed May 24, 1972, Ser. No. 256,632

Term of patent 14 years

Int. Cl. D7—03

U.S. Cl. D7—137

FIG. 1 is a front view of a spoon showing my new design;

FIG. 2 is a rear view thereof;

FIG. 3 is a side view thereof, the undisclosed side being substantially identical with the side shown in FIG. 3;

FIG. 4 is an enlarged cross-section taken on line 4—4 of FIG. 1.

FIG. 5 is an enlarged cross-section taken on line 5—5 of FIG. 1.

I claim:

The ornamental design for a spoon or similar article, substantially as shown and described.
